UNITED STATES PATENT OFFICE

EARL W. CAULDWELL, OF LEMONT, ILLINOIS

HAMMER

Application filed November 13, 1928. Serial No. 319,168.

This invention relates to hammers, and more particularly to means for connecting the head and handle of a hammer, hatchet or similar implement.

5 An important object of the invention is to provide a wedging means for securing the handle in the head, of such character that the lower ends of a pair of inserted wedges are spread apart after their insertion, there-
10 by expanding the handle to cause the same to tightly fit within the hammer head.

A further object of the invention is to pro-
15 vide wedging means of this character which may be readily inserted and in which the spreading of the wedges is readily accom-
plished by the insertion of a further wedge, which also assists of itself in spreading the material of the handle.

A still further object of the invention is
20 the provision of means preventing the de-
tachment of the handle from the head, even
though the handle becomes slightly loosened,
thus permitting continued use of the hammer
until the wedging means employed may be
25 conveniently tightened.

These and other objects I attain by the con-
struction shown in the accompanying draw-
ings, wherein for the purpose of illustration
is shown in a preferred embodiment of my in-
30 vention and wherein:

Figure 1 is a longitudinal sectional view
showing means for connecting the heads and
handles of tools constructed in accordance
with my invention;

35 Figure 2 is a section on the line 2—2 of
Figure 1;

Figure 3 is an end elevation of the tool;

Figure 4 is a section on the line 4—4 of
40 Figure 1;

Figure 5 is a perspective view of the wedge
employed with the retaining device.

Referring now more particularly to the
drawings, the numeral 10 generally designates
45 a hammer head, the handle receiving
socket 11 of which increases in size from its
center 12 toward opposite ends thereof. The
rear or claw wall of the socket at its upper
end is concavely curved and rather steeply
50 pitched, as indicated at 13. The handle 14
provided may have its upper end tapered to

extend through the socket from the lower end thereof and to fit the lower end of this socket, and is provided in its rear or claw wall from a point slightly below its upper end to a point adjacent its center with a groove 15. This 55 groove at its lower end communicates with a transversely extending bore 16, the purpose of which will presently appear.

In combination with a head and handle constructed as above described, I provide a 60 wedge 17 shaped to fit against the arcuately curved claw wall of the socket at the upper end thereof and having its inner face straight. This wedge has attached thereto a flexible rod 18, the wedge preferably having an open- 65 ing 19 therethrough from its lower end to its upper end through which the upper end of the rod extends and which opening is enlarged at its upper end to permit heading or riveting of the rod therein, as indicated at 20. 70 When the handle is in position in the socket, this wedge 17 is driven home and the rod 18, which is disposed in the groove 15, is shaped to the handle and has its terminal portion directed through the transverse bore 16. 75 At the opposite end of this bore from the groove, an enlargement is provided, as at 21, within which the opposite end of the rod is headed. The wedge 17 and rod 18 act as a re-
taining means, effectively preventing separa- 80 tion of the hammer head and handle, even though the handle be relatively loose in the socket.

To tighten the handle in the socket, I pro-
vide a wedge assembly comprising transverse 85 wedges 22 and a longitudinal wedge 23. The transverse wedges 22 may be any of the usual blunt wedge types but should be of a length to extend beyond the center 12 of the socket, which forms a restricted throat. The wedge 23 is furcate, having an upwardly tapering notch 24 formed in its lower edge. A pin 25 is directed transversely through the handle between the wedges 22 prior to insertion of the wedge 23 and traverses the socket at a 90 point below the restricted throat 12 thereof.

When the wedge 23 is inserted, the pin 25 engaging adjacent faces of the legs 26 produced by the notch 24, causes these legs to 100 spread and come into contact with the lower

ends of the wedges 22, thereby forcing these lower ends outwardly and bending the same, as indicated at 27 in Figure 1. The wedges 22 are thus rendered unremovable and the outward movement thereof forces the material of the handle into very close engagement with the walls of the socket below the throat. Expansion of the upper end of the handle by the insertion of the wedges 22 and 23 will cause a corresponding expansion of the upper end of the handle, so that the handle is in firm engagement with the walls of the socket throughout and all likelihood of relative movement of the handle and head removed. If any looseness occurs in use, this looseness may be readily removed by setting up the wedges 22 and 23.

Since the construction hereinbefore set forth is capable of a certain range of change and modification without materially departing from the spirit of the invention, I do not limit myself to such specific structure except as hereinafter claimed.

I claim:

In combination with a tool head having a handle receiving socket increasing in size from its center toward opposite ends thereof, a handle inserted in the socket from the lower end thereof and fitting such lower end, a wedge member inserted between an end wall of the socket, and the handle at the upper end of the socket, and a rod secured to the wedge member and extending downwardly through the socket and secured at its opposite end to the hammer handle, said handle having a groove in its rear face for the reception of said rod, the lower end of the groove communicating with a transverse bore through which the rod is directed, the opposite end of the rod being headed at the end of the bore remote from the groove.

In testimony whereof I hereunto affix my signature.

EARL W. CAULDWELL.
